UNITED STATES PATENT OFFICE.

THEODORE SUSEMIEL, OF NEW YORK, N. Y., ASSIGNOR TO THE J. L. MOTT
IRON WORKS, OF SAME PLACE.

BASIN-PLUG.

SPECIFICATION forming part of Letters Patent No. 425,113, dated April 8, 1890.

Application filed February 12, 1890. Serial No. 340,133. (No model.)

To all whom it may concern:

Be it known that I, THEODORE SUSEMIEL, a citizen of the United States, residing in the city, county, and State of New York, have 5 invented a new and useful Improvement in Basin-Plugs, of which the following is a specification.

Basin-plugs have heretofore been made entirely of metal or of metal parts screwed together and holding and compressing a ring of rubber; but these devices are heavy, and when accidentally dropped are liable to crack, chip, or otherwise mar and injure the surface of a bath or basin.

15 The object of my invention is to construct a basin-plug as light in weight as is consistent with strength, so that the risk of injuring the surface of a bath or basin is reduced to a minimum.

20 In carrying out my invention I employ sheet metal in the construction of the body of the plug, which is composed of a cup-shaped piece of sheet metal stamped up, with a central recess and opening and an inclined 25 periphery. A rubber ring that is sprung around said inclined periphery and top and bottom plates, centrally perforated, a knob and chain-ring, and a central connecting screw-lug are used, by which the parts are 30 held together.

In the drawings, Figure 1 is an elevation, and Fig. 2 a vertical section, of my improved basin-plug.

a represents the circular cup-shaped piece 35 of sheet metal, stamped up with a central recess at *a'* and opening *l* and an inclined periphery or edge *b*, around which the rubber ring *c* is sprung. The top plate *d* is centrally perforated, and preferably has a ribbed edge 40 *d'*, adapted to set over the upper edge of the inclined periphery *b* and extend beyond and partially over the top edge of the rubber ring *c*. This top plate *d*, I prefer to arch with the convex side uppermost. The bottom plate *e*

is of larger diameter than the base of the 45 cup-shaped piece *a*, and therefore extends partly over the base of the rubber ring *c*, and by these top and bottom plates the rubber ring is retained in place. This bottom plate 50 has a recess *e'* and central opening conforming to that of the cup-shaped piece *a*, and the connecting-screw *f* passes through the central openings in the parts *a*, *d*, and *e*, and the head of the screw *f* is received within the recess of the bottom plate *e*, and is thereby 55 in effect countersunk, where it cannot come in contact with the bath or basin to injure the same. The knob *g* has a central screw-threaded opening to engage with the screw *f* in connecting and securing the parts together, and 60 said knob is provided with a chain-ring *g'*.

My improved basin-plug is light in weight, but of ample strength, and the same is not at all likely to injure the surface of a bath or basin with which it may be forcibly brought 65 in contact.

I claim as my invention--

1. The combination, with the connecting-screw *f*, knob *g*, and ring *g'*, of the cup-shaped body *a*, of sheet metal, stamped up with an 70 inclined periphery or edge *b*, the rubber ring *c*, and the top and bottom plates *d* *e*, substantially as set forth.

2. The combination, with the connecting-screw *f*, knob *g*, and ring *g'*, of the cup-shaped 75 body *a*, of sheet metal, stamped up with an inclined periphery or edge *b*, a recess *a'*, and central opening, the rubber ring *c*, the bottom plate *e*, having a recess and central opening, and the top plate *d*, having a central 80 opening and ribbed edge *d'*, substantially as set forth.

Signed by me this 7th day of February, A. D. 1890.

THEODORE SUSEMIEL.
